UNITED STATES PATENT OFFICE

116,016

DESIGN FOR A COMBINED BOTTLE AND CLOSURE THEREFOR

John D. Buckingham, Chicago, Ill., assignor to
Lucien Lelong, Inc., Chicago, Ill., a corpora-
tion of Illinois

Application May 1, 1939, Serial No. 84,711

Term of patent 7 years

To all whom it may concern:

Be it known that I, John D. Buckingham, a citizen of the United States and a resident of the city of Chicago, in the county of Cook and State of Illinois, have invented a new, original, and ornamental Design for a Combined Bottle and Closure Therefor, of which the following is a specification, reference being had to the accompanying drawing, forming a part thereof.

On the drawing:

Figure 1 is a front or rear elevational view of

the combined bottle and closure therefor, showing my new design, with the bottle and closure shown separate.

Figure 2 is a side-elevational view; and

Figure 3 is a top plan view thereof, with the closure shown in Figure 1 omitted from these two figures.

I claim:

The ornamental design for a combined bottle and closure therefor, as shown.

JOHN D. BUCKINGHAM.
